FOLDABLE SEAT

Roy E. Burch, Midland, Mich.

Application April 21, 1948, Serial No. 22,365

1 Claim. (Cl. 155—133)

1

This invention relates to a foldable seat structure adapted to be associated with backless benches or plank bleachers such as used in football stadiums, grandstands, and similar buildings.

One of the prime objects of the invention is to design a very simple, practical, and relatively inexpensive, lightweight, foldable seat structure which can be readily folded into a compact bundle for easy carrying and/or storage, and which is provided with flexible canvas or cloth seat and backrest sections to prevent the user's clothing from contact with the surface of the stadium bench or plank, and provide a comfortable backrest, enabling the owner to relax in comfort and enjoy the spectacle or game being played.

A further object is to provide an adjustable seat which can be readily adjusted to suit benches or planks of varying widths and/or size.

Still a further object is to design a lightweight seat which can be readily manufactured and assembled, and which is foldable into a compact bundle for convenient and easy transportation from place to place.

With the above and other objects in view, the present invention consists in the combination and arrangement of parts, hereinafter more fully described, illustrated in the accompanying drawing, and more particularly pointed out in the appended claim, it being understood that changes may be made in the form, size, proportion, and minor details of construction, without departing from the spirit, or sacrificing any of the advantages of the invention.

In the drawing:

Fig. 1 is a perspective, elevational view of my foldable seat, showing it in place on a plank such as customarily serves as a stadium seat.

Fig. 2 is a side-elevational view thereof.

Fig. 3 is a fragmentary, side-elevational view illustrating the adjustable leg.

Fig. 4 is a view showing the seat folded for carrying.

Referring now more specifically to the drawing in which I have shown the preferred embodiment of my invention. The numeral 5 indicates the plank or raised bench such as found in stadiums in general, and this is usually formed of a single piece of material of standard width, or it may comprise spaced-apart sections of the same general width.

My foldable seat comprises a back frame 6, bowed as clearly shown in Fig. 1 of the drawing, and spaced apart legs 7 and 8 are pivotally connected to the end sections 9 of this bowed back at a point spaced from the lower ends thereof by means of pins or bolts 10, the lower end sections 9 of the back frame bearing against the rear edge of the plank, and as clearly shown in Fig. 2.

These legs 7 and 8 are adjustable as to length, the one end being threaded as at 11, and one

2

end 12 of a hook member 13 has threaded engagement therewith, the opposite end 14 being turned inwardly to form substantially U-shaped hooks which fit over the front edge of the plank 5, and it will be obvious that these legs can be adjusted as desired by threading the member 13 into or out of the legs, and then tightening the locking nut 15 to hold it in set position.

The upper section of the bowed back frame 6 is bent rearwardly as shown at 16 and a cloth or canvas 17 spans said frame and is secured thereto in any approved manner to form a comfortable and flexible backrest, and looped tabs 18 are provided on this cloth backrest and for a purpose to be presently described.

A similar cloth or canvas strip 19 spans the legs 7 and 8, and forms the seat of the structure, and these members 17 and 19 are readily washable so that a clean, neat appearing structure can be had.

In practice, the structure is set up as clearly shown in Figs. 1 and 2 of the drawing. The hook-shaped end sections 13 of the legs are adjusted to span the support 5 and the structure is then ready for use, providing a comfortable and clean chair which can be easily and quickly set up and/or folded for carrying purposes or folded for storage when not in use.

From the foregoing description, it will be obvious that I have perfected a very simple, practical and inexpensive foldable seat structure, which is convenient in use, and which can be folded into a very compact bundle for carrying or storage.

35 What I claim is:

A foldable seat structure adapted to be mounted on a backless support, and comprising a bowed backframe, a pair of internally threaded adjustable legs pivotally connected to the lower end sections of the bowed back frame at a point spaced from the free ends thereof, longitudinally adjustable U-shaped end hooks forming part of said legs, one end of each U-shaped hook being threaded for engagement with one of said legs, locking means for securing the hooks in adjusted position, a flexible backrest spanning said back frame, and tabs on said flexible backrest and accommodating the free ends of the U-shaped members for securing the seat in its folded position.

ROY E. BURCH.
